UNITED STATES PATENT OFFICE

THOMAS E. GJORUP, OF CHICAGO, ILLINOIS

POWDER PUFF

Application filed July 21, 1928. Serial No. 294,424.

This invention relates to improvements in powder puffs and its chief object is to provide a sanitary powder puff that is attractive in appearance, readily washed or cleaned and that is so constructed that the powder contained therein is kept clean and ready for instant use at all times.

With the foregoing and other objects in view the invention consists in the combination and arrangement of parts to be herein-after fully described, pointed out in the claims and illustrated in the accompanying drawing which forms a part of this application for patent and in which—

15 Fig. 1 is a plan view of the powder puff.

Fig. 2 is a sectional view through the casing and cover for the powder pad.

20 Fig. 3 is a similar view, the casing having been reversed or turned inside out previous to insertion of the powder pad.

Fig. 4 is a slightly enlarged view, partly in section, of a slightly different form of powder pad.

25 Fig. 5 is an enlarged fragmentary sectional view of the casing.

Like reference characters denote corresponding parts throughout the several views.

The present powder puff comprises a pad by means of which the powder is applied to the skin in the usual manner, this pad may either comprise a piece of chamois or any other suitable powder-carrying material, that is material that is generally used and to which the powder may cling, and a rubber sponge loosely carried therewithin, the disc-like sections of the powder-carrying material being cemented or otherwise secured together along their meeting edges; or the powder pad may comprise a layer of powder-carrying material secured to each flat face of a disc-like rubber sponge, the pad in both cases being carried in a container made of rubber or like material, said container being reversible so that it may be turned wrong side out when one side is soiled.

The reference numeral 1 denotes the receptacle made of soft rubber or like material, of round or disc-like shape comprising the base 2 and the mouth 3 which is surrounded by the lip or flange 4. A flat rubber cover 5, 50 circular in shape, is cemented at a point 6 to the flange 4. A plan view of this receptacle or container is shown clearly in Fig. 1. This receptacle is adapted to receive the powder pad which may comprise the chamois 55 7 comprising two pieces of material cemented together as shown at 8 and containing the rubber sponge 9 as shown in Fig. 4, or the sponge 9 may have secured to its opposite faces the layers or flat pieces of material 60 10, 11.

The powder is carried upon the pad and access to the same is had by opening the flap 5 through the mouth 3 as shown in Fig. 5 thus exposing the pad surface containing the 65 powder, this exposed surface may now be applied to the skin without removing the pad from the container. At any time the receptacle 1 may be reversed, turned inside out, as shown in Fig. 3, the cover 5 now appearing uppermost but normally serving as a closure for the mouth 3 and so protecting the powder pad and to use the pad the cover 5 is merely raised to expose the pad which is then applied to the skin. If preferred the 70 pad can be removed instantly from the receptacle and used. Powder may be carried in the receptacle if desired so that the pad is readily washable and as it is provided with a 75 sponge in its interior will dry quickly and is ready again for use. The receptacle 1 can be used to tap the skin gently as is usually done with a puff to cause the skin to "take up" the powder and it is therefore more than 80 merely a container but an essential part of the puff.

What is claimed is:—

1. In a powder puff, a circular disc-shaped rubber sponge, powder-carrying material se-

cured to the opposite faces of said sponge but leaving the circumferential edge thereof exposed, and a container for said sponge and powder-carrying material.

5. 2. In a powder puff, a flexible reversible receptacle having a mouth portion, an annular lip defining said mouth portion, a reversible disc-shaped pad removably disposed within said receptacle and having one face wholly exposed in the open position of said mouth portion, and a cover cemented at one point to said lip and adapted as a closure for said mouth portion.

10. In testimony that I claim the foregoing as my own, I have hereto affixed my signature.

THOMAS E. GJORUP.
